UNITED STATES PATENT OFFICE.

LEON GSCHWIND, OF YOUNGSTOWN, OHIO.

WASHING MACHINE.

Application filed June 16, 1920. Serial No. 389,412.

To all whom it may concern:

Be it known that I, LEON GSCHWIND, a citizen of the United States, residing at Youngstown, in the county of Mahoning and State of Ohio, have invented certain new and useful Improvements in Washing Machines, of which the following is a specification.

My invention relates to improvements in washing machines and refers particularly to a machine adapted for use in washing dishes, although it may be used in cleansing garments or for any other purpose where it would perform the desired function.

15 The main object of my invention is the provision of a structure which may be used in connection with the sink or basin employed in a residence or apartment to adapt such sink or basin for use of my improvements to enable a quick and thorough washing of dishes or for other purposes, and which will not interfere with the usual purposes of the basin or sink.

Another object of my invention is the provision of a mechanism capable of ready application, with slight modification, to sinks and basins in general use, and which may be operated by hand or by power to quickly clean the crockery or other objects 30 found necessary.

Another object of my invention is the provision of a mechanism of the character and for the purposes stated, which will be of simple, durable and inexpensive construction, which will be small and compact in size to permit installation in a very small space, and which will prove efficient and practical in every particular.

With these ends in view, my invention 40 consists of a mechanism embodying novel features of construction and combination of parts, substantially as shown, described and particularly defined and distinguished by the claim.

45 The construction in detail and the operation of my improvement, as well as its many advantages, will be readily understood from the accompanying drawings, in which:

50 Figure 1 represents a vertical sectional view of the novel form of basin in connection with which my mechanism is em-

ployed, the basin element being in normal position.

Fig. 2 represents a top plan view of the 55 basin structure, the basin being removed.

Fig. 3 represents a vertical central sectional view of the complete basin structure showing the dish-washing receptacle and my mechanism in applied position, with the 60 basin member inverted and occupying the position in which it is placed when the invention is used as a dish-washing machine, and

Fig. 4 represents an elevation of the driving mechanism or operating unit of my invention.

Referring by numeral to the drawings, in which similar numerals are employed to designate the same parts in all of the views: 70

The numeral 1 designates the back wall, 2 designates the basin structure, and 3 designates a depending chamber or receptacle formed integral with the back wall 1, and provided with an annular seat 4, to receive, 75 when the basin is in normal position, the flange 5 of the basin, as most clearly seen in Fig. 1.

This construction provides a practical basin for the usual purposes, while the back 80 wall is formed with the depending chamber or receptacle, such chamber or receptacle being provided with a drain or outlet 6 and with a central shaft-opening 7, provided with a surrounding threaded portion 8, 85 while mounted within the receptacle and supported above the bottom thereof is the dish-receiving basket or member 8'.

Upon the under side of the receptacle in suitable ways or supports 9, is mounted the 90 base 10, of a suitable motor 11, whose driving shaft 12, carries a gear 13, meshing with the large gear 14, on the shaft 15, bearing in the yoke-shaped depending hanger or bracket 16, said shaft being disposed horizontally and carrying upon its inner end the small bevel pinion 17, meshing with the bevel pinion 18, on the vertical shaft 19, such shaft having its lower portion 19', bearing in the bracket, and its upper portion bearing in the threaded cap 20, and the opening of the basin receptacle, while said upper end is formed with a squared portion 22, to receive the agitator 21, the operation

of which upon the rotation of the shaft effects the cleansing of the dishes contained in the basket, as will be readily understood.

In use the basin proper is inverted, as shown in Fig. 3, and a suitable amount of hot water is placed in the receptacle with the dishes or other objects to be cleaned being in the basket provided for such purpose, the motor driving the shaft and rotating the agitator, causing the hot water to be circulated throughout the entire basket and cleansing thoroughly the dishes or objects therein.

It will be readily understood that a motor of any proper kind may be employed, or the mechanism may be driven by hand, and in either event the machine will operate in a practical and effective manner, and such

a mechanism will commend itself as highly useful and desirable in homes or apartments, as well as in other situations.

I claim:

In a mechanism of the character described, the combination with a receptacle having its bottom formed with a central opening and ways adjacent said opening, a shaft mounted in said opening, a base carrying a motor and fitting in the ways on the bottom of the receptacle, a yoke depending from said receptacle and forming a mounting for said shaft, and gearing connecting the motor and said shaft.

In testimony whereof I affix my signature.

LEON GSCHWIND.
